UNITED STATES PATENT OFFICE.

EDWARD B. WEED, OF CLEVELAND, OHIO, ASSIGNOR TO WEED DISTILLING AND MANUFACTURING COMPANY, OF NEW YORK, N. Y., A CORPORATION OF NEW YORK.

DISTILLATION OF WOOD.

No. 806,606.

Specification of Letters Patent.

Patented Dec. 5, 1905.

Application filed February 15, 1901. Renewed April 10, 1905. Serial No. 254,721.

To all whom it may concern:

Be it known that I, EDWARD B. WEED, a citizen of the United States, residing at Cleveland, in the county of Cuyahoga and State of 5 Ohio, have invented certain new and useful Improvements in the Distillation of Wood, of which the following is a specification.

The invention relates particularly to cutting or otherwise preparing resinous wood so 10 that a large surface area may be acted upon by a liquid bath of rosin or similar material in which the wood may be wholly or partly immersed in order to extract the turpentine and similar desired products therefrom.

15 In the drawings, Figure 1 represents a block of wood, showing the cuts or recesses made from one side. Fig. 2 is a cross-section on the line 2 2 of Fig. 1. Fig. 3 represents a block of wood in which the cuts are made 20 from opposite sides. Fig. 4 is a cross-section on the line 4 4 of Fig. 3. Fig. 5 is a plan view showing how the wood may be piled when placed in a still.

The wood is first divided into blocks *a*, 25 from one to eight feet in length, having any desired thickness, preferably, however, being from three to twelve inches thick. The blocks are sawed crosswise of the grain to form cuts or slots *b* therein, that extend within a short 30 distance of the opposite edge of the block. These cuts are made so that the length of the sections *c* will be greater than the thickness of the uncut portion of the block and are made at suitable distances apart, preferably 35 from one to three inches. If desired, the cuts may be made from opposite sides of the block, as shown in Fig. 3. The sections are held together by the uncut portion of the block and can therefore be easily handled. As the length 40 of the sections is greater than the width of the uncut portion, a number of blocks can be piled on top of each other in a still, as shown in Fig. 5, without interposing means to hold same apart. The wood thus prepared and 45 placed in the still is covered by a bath hav-

ing a higher boiling-point than the desired product to be obtained and is distilled. The bath which is at present employed for this purpose consists of rosin.

It has been observed that the desirable products, such as turpentine, exude from the pores of the wood, and by making cuts or slots therein, as above described, the area subjected to the action of a bath in which the wood may be immersed is greatly increased and the 50 largest possible number of pores of the wood are exposed. The slots permit a bath such as described to circulate freely and come into contact with the exposed surfaces, although the blocks may be piled on top of each other 55 to a considerable height. As the sections are held together by the uncut portion of the blocks, the wood can be handled more easily than otherwise is possible, and therefore can be handled at less expense. This method of 60 preparing the wood also obviates the necessity of interposing means to hold the sections apart in order that the surfaces of the sections may be subjected to the action of the 65 bath.

70 I claim as my invention—

1. The improvement in the distillation of wood which consists in slotting blocks of wood crosswise of the grain, immersing the slotted blocks in a bath the boiling-point of which 75 is higher than the product to be obtained, and distilling the same.

2. The improvement in the distillation of wood which consists in slotting blocks of wood crosswise of the grain, immersing the slotted blocks in a bath of rosin, and distilling the same.

In testimony whereof I sign this application, in the presence of two witnesses, this 26th day of January, 1901.

EDWARD B. WEED.
